UNITED STATES PATENT OFFICE.

WILLIAM B. GHARST AND GUSTAV KARL, OF MASON CITY, IOWA.

STOCK LOADER.

Application filed January 4, 1923. Serial No. 610,585.

To all whom it may concern:

Be it known that we, WILLIAM B. GHARST and GUSTAV KARL, citizens of the United States, residing at Mason City, in the county 5 of Cerro Gordo and State of Iowa, have invented certain new and useful Improvements in Stock Loaders; and we do declare the following to be a full, clear, and exact description of the invention, such as will enable others skilled in the art to which it 10 pertains to make and use the same.

Our invention relates to improvements in stock loaders of the gang-way type provided with an inclined floor and a pair of 15 parallel side walls, such devices being used when loading stock into wagons, trucks or cars, and when unloading.

It is one object of the invention to provide an extremely simple and inexpensive 20 device of the character set forth which although being rigid for use, may be readily folded into substantially flat form to be carried from one place to another or when it is desired to store the device for future 25 use.

In carrying out the above end, a further object is to provide a novel arrangement of parts for rigidly reinforcing the inclined floor and for pivotally connecting the vertical sides with said floor in such a manner 30 that they may be folded inwardly into overlapped relation.

A still further aim is to provide unique 35 means for holding one of the side walls rigidly in upright position and additional means extending from said one wall to the other wall to rigidly support the latter.

With the foregoing in view, the invention resides in the novel subject matter hereinafter described and claimed, the description 40 being supplemented by the accompanying drawings.

Figure 1 is a side elevation of a loader 45 constructed in accordance with our invention.

Figure 2 is a top plan view.

Figure 3 is a longitudinal sectional view as indicated by line 3-3 of Fig. 2.

Figures 4 and 5 are vertical transverse 50 sections on lines 4-4 and 5-5 of Fig. 1.

Figure 6 is a top plan view of the device folded for storage.

Figure 7 is a transverse sectional view on line 7-7 of Fig. 6.

55 In the drawings above briefly described, the numeral 1 designates an inclined floor

which is preferably formed of a plurality of planks having transverse cleats 2 secured to their upper sides. Transverse metal bars 3 are secured to the lower side of the floor 1 and have their end portions bent upwardly as indicated at 4 to form rigid upstanding arms, the arms at one edge of the floor being of greater length than those at the opposite edge. In forming the arms 4, the 60 end portions of the bars are bent to form eyes 5 and from these eyes, the metal extends downwardly at 6 and is bent inwardly at 7 beneath the horizontal portions of the bars. Bolts, rivets or the like 8 are employed to secure the bars 3 to the floor 1 and the endmost of these fasteners may well pass also through the inwardly bent ends 7. Longitudinal slats 9 are preferably secured to the upturned bar ends to form parts of 70 the side walls which rise from the floor. The major portions of these walls however are formed of spaced slats 10 and metal bars 11 secured to said slats, the lower ends of said bars 11 being bent to form eyes 12 75 which are horizontally alined with the eyes 5. Suitable pivot rods 13 are passed through the alined eyes 5 and 12 at each edge of the floor 1 and it will thus be seen that pivotal connections are established between the side walls of the floor, permitting these side walls to fold inwardly into overlapping relation with each other, as shown in Figs. 6 and 7. By having the upturned 80 ends of the bars 3 of different lengths at opposite edges of the floor 1, the side walls will more compactly fold than otherwise.

For the purpose of holding one of the side walls rigidly in upright position, we provide a plurality of vertically alined eyes 95 14 and a removable bolt 15 passing therethrough, said bolt extending across the hinge line as clearly shown in Figs. 1 and 5. To support the other side wall in vertical position, we provide suitable means, such as transverse spacing rods 16 pivoted to the one wall and engageable with eyes 17 on the other wall, these rods being positioned at a suitable elevation to permit the stock to pass beneath them.

To properly support the upper end of the floor 1, we employ suitable pivoted legs 18 connected by appropriate braces 19, bracing rods 20 being provided to hold the legs in operative position. These rods are preferably pivoted to the edges of the floor 1 and are provided with hook and eye connections

21 by means of which they are operatively attached to the legs.

By employing the construction shown or a substantial equivalent thereof, it will be seen that a simple and inexpensive device is provided for loading and unloading stock expeditiously. When the device is not in use, release of the rods 16 and 20 and removal of the bolt 15 will permit the entire device to be compactly folded, in which condition it may be easily carried from one place to another and may be stored in little space.

As excellent results may be obtained from the details disclosed, they are preferably followed, but within the scope of the invention as claimed, numerous minor changes may be made.

We claim:

20. A knock-down stock loader comprising a floor, transverse metal bars secured to the

underside of said floor and having their ends directed upwardly and bent to form eyes, the extremities of the bars being bent downwardly against said upwardly directed portions and then bent inwardly under and secured to the under-faces of the horizontal portions of the bars, a pair of inwardly foldable side walls having metal bars whose lower ends are formed with eyes 25 aligned with those aforesaid, removable pivot-rods passing through the aligned eyes, vertically aligned eyes on the floor and on one of said side walls, a removable bolt received in said eyes to hold said one wall in upright 30 position, and releasable means extending from said one side wall to the other wall for holding the latter upright.

In testimony whereof we have hereunto affixed our signatures.

WILLIAM B. GHARST.
GUSTAV KARL.
